(57) **CLAIM**

The ornamental design for a wireless remote controlled toy snowmobile, as shown and described.

DESCRIPTION

FIG. 1 is a front elevational view of the wireless remote controlled toy snowmobile of the present invention;
FIG. 2 is a rear elevational view of the wireless remote controlled toy snowmobile of FIG. 1;
FIG. 3 is a left side elevational view of the wireless remote controlled toy snowmobile of FIG. 1;
FIG. 4 is a right side elevational view of the wireless remote controlled toy snowmobile of FIG. 1;
FIG. 5 is a top plan view of the wireless remote controlled toy snowmobile of FIG. 1; and,
FIG. 6 is a bottom plan view of the wireless remote controlled toy snowmobile of FIG. 1.
